UNITED STATES PATENT OFFICE.

EDGAR N. EAMES, OF MONTCLAIR, NEW JERSEY.

DESIGN FOR PRINTED TEXTILE FABRIC.

No. 37,523.

Specification for Design.

Patented Aug. 29, 1905.

Application filed June 5, 1905. Serial No. 263,884. Term of patent 7 years.

To all whom it may concern:

Be it known that I, EDGAR N. EAMES, a citizen of the United States, residing at Montclair, in the county of Essex and State of New Jersey, have invented a new, original, and ornamental Design for Printed Textile Fabrics, of which the following is a specification, reference being had to the accompanying drawing, forming part hereof.

The figure is a plan view of the fabric, showing my new design.

I claim—

The ornamental design for a printed textile fabric as shown.

EDGAR N. EAMES.

Witnesses:

JOHN COLBY,
DAVID DOUGLASS.
